Specification for Design.

Patented Dec. 14, 1915.

Application filed September 10, 1915. Serial No. 50,097. Term of patent 14 years.

To all whom it may concern:

Be it known that I, CHARLES F. SIMMS, a citizen of the United States, residing in the city of Attleboro, county of Bristol, and State of Massachusetts, have invented a new, original, and ornamental Design for a Handle for Spoons, Forks, or Similar Articles, which is illustrated in the accompanying drawing, forming part of this application.

Figure 1 in the drawing is a view of the

design in front elevation. Fig. 2 is a view of the design in rear elevation. 3 is a fragmentary perspective view on the line $x-x$ of Fig. 1.

What I claim is:

The ornamental design for a handle for spoons, forks or similar articles, as shown.

CHARLES F. SIMMS.
